(57) **CLAIM**

The ornamental design for a driving recorder for a bicycle, as shown and described.

DESCRIPTION

FIG. 1 is a front perspective view of a driving recorder for a bicycle showing our new design;

FIG. 2 is a rear perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is a front perspective view thereof, shown in condition of use with a mount disclosed in broken lines to illustrate an environment.

The broken lines depict portions of the driving recorder for a bicycle in which the design is embodied that form no part of the claimed design. The broken lines showing a mount in FIG. 9 represent environmental structure and form no part of the claimed design.
